UNITED STATES PATENT OFFICE

2,518,505

HEADLAMP FOR MOTOR VEHICLES

Ray P. Teele, Jr., Berkeley, Calif., assignor to the
United States of America as represented by the
Secretary of Commerce

Application March 31, 1944, Serial No. 528,915

2 Claims. (Cl. 240—46.53)

(Granted under the act of March 3, 1883, as
amended April 30, 1928; 370 O. G. 757)

1

The invention described herein may be manufactured and used by or for the Government of the United States for governmental purposes without the payment to me of any royalty thereon in accordance with the provision of the Act of April 30, 1928 (Ch. 460, 45 Stat. L. 467).

My invention relates to a headlamp for motor vehicles for driving under "blackout" conditions.

In the accompanying drawings:

Figure 1 is a side elevation of my complete headlamp;

Figure 2 is a front elevation;

Figure 3 is a section on the line 3—3 of Figure 2;

Figure 4 is a section on the line 4—4 of Figure 3;

Figure 5 is a detail of the light emitting aperture as seen from 5—5 of Figure 3.

In the drawings a housing 11 is provided with a face plate 12 on which there is rigidly mounted a hood 13 having a substantially horizontal margin 14 and has rigidly mounted therein a louver 15, approximately parallel with the face plate 12, with a lower edge 16 of substantially trapezoidal shape. Within the housing 11 is a bracket 17 carried by the face plate 12. This bracket supports a lamp socket 18 and a mirror 19. Mounted in the socket 18 is a lamp 20 having a filament 21. The face plate 12 is provided with a trapezoidal-shaped aperture 22 wholly above the margin 14 of the hood 13 and is closed by means of a light transmitting plate 23 secured to the face plate 12 by any suitable means. The light from the filament 21 and that reflected by the mirror 19 passes through the aperture 22 in the face plate 12 and falls on the opaque louver 15 which obstructs all but those downwardly directed rays which are permitted to pass the controlling lower edge 16 of the louver 15 and the margin 14 of the hood 13. The lateral spread of the light is controlled by the sides of the approximately trapezoidal aperture 22 and the louver 15.

My headlamp produces a beam of predictable and controlled intensity, direction and distribution to comply with the blackout standards and/or regulations of the War Department. Vehicles equipped with my headlamp may be operated at night with a minimum of danger of their presence and movement being detected by observers in airplanes.

It should be understood that the present disclosure is for the purpose of illustration only.

2

and that the invention includes all modifications and equivalents which fall within the scope of the appended claims.

What I claim is:

5 1. An attachment for headlights for motor vehicles for restricting highway illumination comprising an opaque cover plate provided with an approximately trapezoidal aperture in the upper portion thereof, means for detachably mounting said cover plate on a headlight, an opaque hood of substantially egg shaped curvature rigidly secured to said plate and shielding said aperture, and an opaque louver within said hood having a reentrant lower margin restricting emerging rays to those which pass below a horizontal plane and do not diverge materially before reaching a highway surface.

2. An attachment for headlights for motor vehicles for restricting illumination, comprising an opaque cover plate provided with an upwardly tapered trapezoidal aperture in the upper portion thereof, means for rigidly and detachably mounting said cover plate on a headlight, an opaque hood of substantially egg shaped curvature rigidly secured to said plate and shielding said aperture, and an opaque louver within said hood parallel with said cover plate having a lower margin cut out to leave an upwardly tapered trapezoidal notch, whereby only rays reflected downwardly by said hood may emerge from said headlight.

RAY P. TEELE, JR.
